CONCRETE ROAD JOINT

Clifford Older, Wilmette, Ill.

Application June 25, 1938, Serial No. 215,748

4 Claims. (Cl. 94—18)

The present invention relates to concrete road joints, and is particularly concerned with load transmission devices for concrete road joints. This application is a continuation-in-part of my prior application, Serial No. 110,960, filed November 16, 1936, for Concrete road joints.

One of the objects of the invention is the provision of an improved concrete load transmission means by means of which the deflection from the normal or no-load plane or position of the roadway to the position under load is reduced to a minimum.

Another object of the invention is the provision of an improved load transmission arrangement in which vertical play is eliminated and in which the doweling structure is as stiff as possible with respect to the vertical deflection of the concrete sections at the joint.

Another object is the provision of an improved doweling structure for concrete road joints which is of maximum stiffness and in which the tendency of the dowel member to split or spread the parts of the concrete section in which the dowel member slides is resisted by an improved structure that practically eliminates any possibility of deflection due to splitting action.

Another object is the provision of an improved doweling structure by means of which the forces applied to the ends of the concrete sections by the dowels are distributed over a wider area and by means of which the tendency toward splitting of the sections of concrete at the dowels is effectively resisted.

Other objects and advantages of the invention will be apparent from the following description and the accompanying drawings, in which similar characters of reference are employed throughout the several views.

Referring to the two sheets of drawings, Fig. 1 is a fragmentary vertical sectional view, taken on a plane passing through the axis of the dowel, of a portion of the concrete roadway comprising the adjacent sections of concrete and a doweling structure constructed according to the invention shown in connection with one form of expansion joint;

Fig. 2 is an end elevational view of the doweling structure, separate and apart from the concrete, taken from the right end of the structure of Fig. 1;

Fig. 3 is a view similar to Fig. 1 of a modification in which both ends of the doweling structure are constructed the same as the right hand end of Fig. 1;

Fig. 4 is another similar view of a modification

in which the reinforcing and anchoring wings of Figs. 1 and 2 have been widened until they engage and assist in the support of an anchoring flange;

Fig. 5 is a similar view of another modification, in which the face flange of each fitting has been wholly eliminated and the anchoring flange is wholly carried by the radially extending wings of the fitting;

Fig. 6 is another view, similar to Fig. 2, of the fitting, taken from the right hand end of Fig. 5, without the concrete.

Fig. 7 is a view similar to Fig. 1 of a modification in which the doweling device is constructed of sheet metal and a rod;

Fig. 8 is an end elevational view, looking from the right hand end of Fig. 7, with the concrete removed;

Fig. 9 is a sectional view, taken on the plane of the line 9—9 of Fig. 8, showing a mode of attachment together of the parts of the doweling device;

Fig. 10 is a fragmentary sectional view of the end of a modified device of the type used at the left side of Fig. 7, in which the sections of the device are held together at the end by a cap, thereby eliminating the necessity for welding;

Fig. 11 is a fragmentary sectional view, taken on the plane of the line 11—11 of Fig. 10, showing the structure of that form of doweling device.

Referring to Fig. 1, the concrete sections are indicated by the numerals 10 and 11, and separated by a space 12, which may be filled by any crushable medium 13, such as an initially plastic, pre-formed filler or separator, or by crushable means, such as fiber wallboard, for example "Celotex." The crushable fillers 13 are of sufficient width to extend from the top to the bottom of the concrete, and are provided with circular bores 14 for receiving the doweling arrangements, further to be described.

The doweling structure may be constructed of cast metal, and it comprises a pair of members having similar anchoring arrangements. For example, the right hand doweling member 15 is a cast metal member which is formed with a cylindrical or tubular body 16 having an inner, machined bore 17 and having a plurality of integral, radially extending wings 18, such as the four wings 18 shown in Fig. 2, which are equally spaced with respect to each other.

The wings 18 extend from one end of the tubular member 16 to the other end, and they act as anchors and as means for transmitting the stress from the doweling member 15 to the concrete section 11.

The wings 18 have the advantage that, irrespective of the rotative position the doweling member 15 may occupy with respect to the plane of the concrete roadway, the wings 18 are just as effective.

The tubular member 16 is preferably provided at the end adjacent the crack 12 with a face flange 19, which is integrally joined to the tubular member 16 and extends at right angles to the axis of the tubular member 16. The face flange 19 may be of any shape in elevation, such as rectangular, hexagonal, octagonal, etc.; but is preferably made circular in shape, as this will accomplish the same result with the use of a minimum amount of metal.

The face flange 19 supports at its outer edge a bearing flange 20, which is cylindrical in shape and integrally joined to the face flange 19. The bearing flange 20 extends backward into the concrete section 11, and by means of the face flange 19 stresses applied to the doweling member 15 are transmitted from the tubular member 16 to the bearing flange 20, which is engaged in the concrete of the section 11. Thus the forces exerted on the doweling structure are distributed. Furthermore, any tendency to split on the part of the concrete 11 at the doweling structure is, of course, resisted by the tubular member 16; but such splitting tendencies are additionally resisted by the cylindrical flange 20, which tends to bind the intermediate portions of the concrete section 11 together, to resist splitting action at the dowel.

The left hand doweling member 21 of Fig. 1 may comprise a solid cylindrical member which is provided with a similar face flange 19 and bearing flange 20 carried by the outer edge of the face flange 19. The doweling member 21 in Fig. 1 is provided with an axially projecting cylindrical rod or dowel member 22, which is machined to be a close sliding fit in the machined cylindrical bore 17.

The doweling member 22 is of such length with respect to the tubular member 16 that there is a space 23 in the end of the tubular member, and the tubular member will wholly accommodate the doweling member 22, so that the face flanges 19 in Fig. 1 may in a contraction joint be placed directly against each other or against a division plate of negligible thickness.

The tubular member 15 is preferably provided with a threaded bore 24 for receiving the threaded rod or set screw 25, which in this case has a laterally turned end 26, so that it can be manipulated by the hand to engage the cylindrical doweling member 22. Thus the member 21 may be placed with its rod 22 in the bore 14 of the filler 13, and the right hand member 15 may be pushed up against the side of the filler, and there secured by means of the set screw 25. By providing a filler 13 of sufficient strength to support the doweling members, the present doweling arrangement may be installed as a unit, with the filler as shown in Fig. 1.

Referring to Fig. 2, this is a modification in which a separate cylindrical dowel rod 27 is provided, slidably mounted in a bore 17, in each of the doweling members 15, both of which are of the same structure as that shown at the right hand of Fig. 1.

In this case the rod may be of such length with respect to the depth of the sockets or bores 17 as to leave spaces 23 for expansion. Both doweling members 15 are secured to the rod 27 by set

screws, as described in Fig. 1, and thus clamped on the filler 13.

Referring to Fig. 4, this is another modification in which the wings, similar to the wings 18, are indicated by numeral 28, because they are of different structure, since the wings have been made wide enough to extend into integral engagement with the bearing flange 20, as well as the face flange 19. In this case the bearing flange 20 is additionally reinforced by being secured to wings 28, and the doweling structure is made stronger by the increased bearing area provided on the wings 28.

Referring to Fig. 5, this is another modification of the structures of Figs. 1-4, in which the face flange 19 has been wholly eliminated and the bearing flange 20 is wholly supported by the radially extending wing flanges 28. This may result in a saving of material by saving the cost of the face flange material, and load is transmitted from the tubular members 16 to the bearing flange 20 by the radial wings 28.

It will thus be observed that I have invented an improved doweling structure for concrete road joints, which may be utilized in either contraction or expansion joints, as distinguished from the devices of the prior art in which there is a tendency for the concrete below and above the doweling members to split off before the doweling member is stressed to full capacity. The present invention is adapted to eliminate the possibility of this destruction of the concrete and to distribute the load throughout the concrete.

The doweling arrangements described herein are of the maximum stiffness, reducing deflection to a minimum, and practically eliminating any lost motion or play. The structure of the present device is such that the forces exerted on the dowel member, tending to spread the doweling members or split the concrete, are more effectively resisted.

The present devices may be constructed at a low cost because they are made of cast metal, and they may be shipped in a knocked-down condition and assembled on the job. As many doweling members may be employed as are considered necessary, the doweling members being preferably spaced regularly along the crack between the concrete sections.

Referring to Figs. 7, 8, and 9, the load transmission devices need not necessarily be constructed of cast metal, as Figs. 7-11 show a mode of sheet metal construction.

In this embodiment, Fig. 7, the dowel rod 40 is of the same construction as previously described, comprising a substantially cylindrical and accurately formed steel member. Two doweling socket members 41 and 42 may, however, be constructed of sheet metal, as follows:

The member 41 may be made of four sheet metal stampings 43 (Fig. 8), each of which has a partially cylindrical portion 44 joined to a pair of radially extending flanges 45, the outer surface 46 of which is located on a radius that is flush with a line passing through the center of the dowel rod 40.

The width of the radially extending flanges or wings 45 at one end 47 is such that it is a substantial fit in the cylindrical flange 48 of a stamped sheet metal face plate 49 and the edge 47 of the wing 45 may be tapered downward toward the left, as shown in Fig. 9, so as to be a drive fit inside the cylindrical flange 38. Thus the face plate 49 may secure the sectional members 43 together to form a member with a cylin- 75

drical bore 50 for receiving the rod 40 and a plurality of wings formed by the flanges 45.

The flanges of which the wings 45 are formed can be spot welded together, as indicated at 51 (Fig. 8), in which case the end of the bar 50 can be closed by means of a stamped sheet metal cap 52, which has a cylindrical flange 53 and a radially extending flange 54. The cylindrical flange is a drive fit in the bore 50.

10 The face plate 49 has a bore 55, which registers with the bore 50 and it engages the end of the wings 45.

In this embodiment also one or more set screws 56 may be provided for clamping the doweling members 41, 42 on the dowel rod 40, as shown in Fig. 1, and for assembling the load transmission device with a crushable filler 57, such as a strip of Celotex, which is adapted to form a space between the two sections of concrete.

15 In other embodiments of the invention, I may dispense with the spot welding 51 between the flanges 45 of the wings and utilize a cap member 58 of substantially cup shape, having an end portion 59 which is adapted to close the bore 50, and a cylindrical portion 60, which engages outside of the cylindrical parts 44 of the members 43. Naturally the cylindrical flange 60 must be provided with a plurality of slots 61 suitably located to pass the wing flanges 45, as shown in Fig. 11. The size of the cap 58 is such that it is a drive fit on the members 43, which it clamps together. All of the parts of the fixtures may be constructed of pressed steel, welded or riveted together, or secured together by caps, as described.

20 Where caps are used and rivets or welds omitted, the caps should necessarily be heavier than otherwise. If desired, the caps and face plate may also be welded in place. In other embodiments of the invention the cap 58 need not be slotted, but it may stop short of the cylindrical flange 60.

25 The operation of the embodiment of Figs. 7-11 is substantially the same as those previously described.

30 The bore 50 is preferably machined after assembly of the members 43, so that it may fit the dowel rod accurately.

35 While I have illustrated a preferred embodiment of my invention, many modifications may be made without departing from the spirit of the invention, and I do not wish to be limited to the precise details of construction set forth, but desire to avail myself of all changes within the scope of the appended claims.

40 Having thus described my invention, what I claim as new and desire to secure by Letters Patent of the United States, is:

45 1. In a doweling structure, the combination of a metal body formed with a socket of uniform cross section, a cooperating metal body formed with an outwardly projecting dowel member, adapted to slide into said socket, outwardly extending flange means carried by one of said bodies, and inwardly extending border flange means carried by one of said bodies for engaging

in the concrete of a roadway to distribute the load on said doweling structure in the concrete.

2. In a doweling structure, a metal body formed with a socket of uniform cross section, adapted to receive a dowel member, said metal body having a plurality of radially extending wings adapted to engage in the concrete of the roadway, said wings being adapted to transmit force applied to said metal body to the concrete and having substantially uniform effective bearing area, irrespective of the rotative position of the metal body in the concrete, said metal body being provided at the outlet of its socket with a face plate and backwardly extending anchoring means carried by said face plate and embedded in the concrete to transmit loads on the metal body to more distant points in the concrete, said backwardly extending means comprising a bearing flange.

3. In a concrete road joint, the combination of crushable means provided with an aperture, with a dowel member extending through said aperture, and a doweling member located on each side of said crushable means, comprising a metal member provided with a socket, said socket having means for engaging the dowel member, whereby the metal members may be secured to the crushable means by clamping on the dowel member, said metal members each being provided with a plurality of radially extending wings for engaging in the concrete, said wings being equally spaced about the periphery of the metal member, whereby the effective bearing area of said wings in the concrete is substantially the same, irrespective of the rotative position of the metal member, said wings supporting a bearing flange located at one end of said metal body and adapted to be engaged in the concrete to transmit forces on said metal body to points spaced from the axis of said metal member.

4. In a load transmission device for concrete road joints, the combination of a compressible spacing member provided with an aperture, said compressible spacing member being adapted to support said load transmission device, and said load transmission device comprising a metal socket member having a cylindrical bore and adapted to receive a cylindrical load transmission member which extends through the aperture in said crushable member, means for supporting said cylindrical member in one of the concrete sections, said socket member slidably engaging said cylindrical member in the other of said concrete sections, said socket member being provided with a face flange engaging the crushable member, and said face flange being provided with an inwardly projecting cylindrical flange, whereby the face flange transmits load to portions of the concrete which are spaced from the cylindrical member, and means for securing said socket member on said cylindrical member, said latter means being adapted to permit the sliding movement of the cylindrical member of the socket member under the stresses developed in the concrete sections.

CLIFFORD OLDER.
